US0D1104056S

(12) United States Design Patent (10) Patent No.: US D1,104,056 S
Kim et al. (45) Date of Patent: * Dec. 2, 2025

(54) DISPLAY SCREEN OR PORTION THEREOF WITH A GRAPHICAL USER INTERFACE

(71) Applicant: Lyft, Inc., San Francisco, CA (US)

(72) Inventors: Young Kyo Kim, San Francisco, CA (US); Rebecca Archangela Frazzano, Boulder, CO (US); Philippe Charles Amilcar Mizrahi, San Francisco, CA (US)

(73) Assignee: Lyft, Inc., San Francisco, CA (US)

() Term: 15 Years

(21) Appl. No.: 29/864,639

(22) Filed: Jun. 8, 2022

(51) LOC (15) Cl. 14-04

(52) U.S. Cl.

USPC D14/488

CLAIM

The ornamental design for a display screen or portion thereof with a graphical user interface as shown and described.

DESCRIPTION

The FIGURE is a front view of a display screen or portion thereof with a graphical user interface showing our new design.

The outermost broken lines show a display screen or portion thereof and form no part of the claimed design. The remaining broken lines show portions of the graphical user interface that form no part of the claimed design.

1 Claim, 1 Drawing Sheet
